WRAPPING PAPER

John W. Elder, Middletown, Ohio

Application October 8, 1941, Serial No. 103,678

Term of patent 14 years

To all whom it may concern:

Be it known that I, John W. Elder, a citizen of the United States, residing at Middletown, county of Butler, and State of Ohio, have invented a new, original, and ornamental Design for Wrapping Paper, of which the following is a specification, reference being had to the accompanying drawing, forming a part thereof.

The figure is a perspective view of a piece of wrapping paper embodying my new design.

The design unit is contained between the broken lines, which is repeated in regular succession as indicated by the extensions beyond the unit boundaries.

I claim:

The ornamental design for wrapping paper, as shown and described.

JOHN W. ELDER.
